MATERNITY GIRDLE

Paula Blatt, Cleveland, Ohio

Application April 15, 1955, Serial No. 501,673

3 Claims. (Cl. 2—41)

The present invention is for an improved maternity girdle.

The object of this invention is to devise a girdle in which the parts thereof may be so cut that, with slight change in the assembly thereof, it may be adapted to be worn with equal efficiency upon a woman with full hips or upon one with slender hips.

Another object is to devise a girdle that can be manufactured in a comparatively simple manner and yet will provide efficient means of support for the abdominal region as well as in the sacroiliac region of the wearer's body.

Other objects will appear from the following description and claims when considered together with the accompanying drawing.

Fig. 1 is a front elevation of my present device in position upon the body of the wearer;

Fig. 2 is a side elevation thereof;

Fig. 3 is a rear elevation thereof; and

Fig. 4 is a view corresponding to Fig. 1 except that it shows another form of this same invention.

It is to be understood that the present form of disclosure is merely for the purpose of illustration and that there might be devised various modifications thereof without departing from the spirit of my invention as herein set forth and claimed.

Referring now to the accompanying drawing, the main body 1 of the girdle may be formed as a one-piece blank of suitable fabric with substantial stretch, that is horizontally when embodied in the present garment or in all directions. This one-piece blank will extend entirely about the buttock and hip region of the body of the wearer and will have its two ends located at the front; the two ends of the blank will be tapered towards a point in each instance so as to have an upper inclined edge and a substantially horizontal lower edge. This particular form of body blank 1 is for the purpose of permitting these front ends to be joined in either of two different manners according to conditions to be mentioned.

Referring to Fig. 1 of the present drawing, the front insert blank 2 of fabric, with one-way stretch horizontally, is of upright trapezoidal form and has its inclined ends sewed to the lower edges of the blank 1, the front end portions of the blank 1 being turned upwardly so as to give the effect of pulling the body part 1 about the body of the wearer when in position upon her body; with the result that there is precluded the necessity of darts at the side of the blank 1 in order to obtain a snug fit. However, in the form illustrated in Fig. 4 of the present drawing, the front insert blank 3 of the same size and shape as in the form of device illustrated in Fig. 1 hereof, is in inverted position and has its ends sewed to the upper inclined edges of the blank 1. This form of garment may be for those who have fuller hips whereas the form of garment illustrated in Fig. 1 hereof may be worn by those who have less fully developed hips.

In each of the two forms above referred to, a longitudinally elastic fabric strip 5 is sewed about the upper

2

edge of the body part 1 and has its ends spaced from each other at the rear where there is provided the reinforcing member 6 of upright trapezoidal form upon the inside of the body part 1 and across the ends of the strip

5. The member 6 is sewed along its end edges to the body part 1, as indicated at 7, and also across the ends of the strip 5, as indicated by reference numeral 8. The member 6 extends above the upper edge of the blank 1 to the extent of the strip 5 and is sewed across the top 10 of the body part 1, as indicated at 9.

In either form of the device, as herein referred to, there is provided the longitudinally elastic strip 10 entirely about the lower edge of the girdle; and detachable garters may be attached to the loops 11 at the bottom 15 thereof.

It will be observed that the single elastic strip 5 forms part of the abdominal support and also part of the supporting means for the sacroiliac region; while the strip 10 forms part of the abdominal support and also extends 20 beneath the buttock of the wearer. Thus this girdle is amply provided with means to prevent it from riding up upon the wearer's body even when stockings are not being worn; and this garment ensures ample feeling of security and comfort in the abdominal and sacroiliac 25 regions of the body of the wearer as well as in the intermediate hip regions.

From the above it will be seen that I have provided a girdle of comparatively simple construction that affords ample and effective and dependable means of supporting 30 engagement in the several regions of the wearer's body, as above mentioned. The present form of garment is comparatively inexpensive because of the standardized form of blanks that may be adapted for use in the manufacture of girdles for differently developed hips of the 35 prospective wearers; with the result that there is ensured the same snugness of fit and the same degree of comfort in all cases. At the same time there is permitted all necessary freedom of movement in this region of the body of the wearer without disturbing the position of 40 the garment.

What I claim is:

1. A girdle comprising a single body of material of legless form with a front portion of reduced height adapted for supporting engagement beneath the abdomen of 45 the body of the wearer and having a rear portion of greater height adapted for engagement over the sacroiliac region of her body and over her buttock and having its intermediate side portions of graduated height adapted for engagement about the hips of the body of the wearer, 50 said body of material having stretch horizontally about the body of the wearer when in position of use thereupon, the side portions of said body of material having upper and lower edges diverging rearwardly from each other from the front towards the rear thereof, a longitudinally 55 elastic strip attached about the top edge portion of said single body and adapted to extend transversely and in an uninterrupted manner beneath the abdominal region of the wearer's body, and a longitudinally elastic strip attached to and extending in an uninterrupted manner 60 about the lower edge of said single body in the region immediately below the wearer's abdomen so as to form part of the supporting means therefor and being adapted for engagement beneath the buttock of the wearer's body when in position of use.

2. The same structure as recited in claim 1 hereof and in which said single body of material has end portions in spaced relation to each other at the front of the girdle, said end portions each having a forwardly and downwardly inclined upper edge and a substantially horizontal lower edge, and an intermediate front horizontally 65 elastic insert of upright trapezoidal form with its side

inclined edges attached to the lower edges of said single body part at the front thereof.

3. The same structure as recited in claim 1 hereof and in which said single body of material has end portions in spaced relation to each other at the front of the 5 girdle, each of said end portions having a forwardly and downwardly inclined upper edge and a substantially horizontal lower edge, and an intermediate front horizontally elastic insert of inverted trapezoidal form with its side inclined edges attached to the upper inclined edges 10 of said single body part.
